United States Patent Office

Des. 183,049
Patented June 17, 1958

183,049

DISPLAY CASE

Frederick S. Holderle, Harvey C. R. Holderle, and Norbert F. W. Holderle, Rochester, N. Y.

Application March 11, 1957, Serial No. 45,194

Term of patent 14 years

(Cl. D80—11)

FIG. 1.

FIG.2.

Fig. 1 is a perspective view of a display case showing our new design, and

Fig. 2 is a perspective view of the same, looking toward the rear of the display case.

The dominant features of the design reside in the full line portions of the drawings.

We claim:

The ornamental design for a display case, as shown and described.
